UNITED STATES PATENT OFFICE.

WILLIAM DOWLING, OF ST. LOUIS, MISSOURI.

MECHANISM FOR OPERATING JAIL-DOORS.

No. 806,960.

Specification of Letters Patent.

Patented Dec. 12, 1905.

Application filed May 25, 1905. Serial No. 262,206.

To all whom it may concern:

Be it known that I, WILLIAM DOWLING, a citizen of the United States, residing at St. Louis, in the State of Missouri, have invented a new and useful Improvement in Mechanism for Operating Jail-Doors, of which the following is a specification.

My invention relates to mechanism for locking, unlocking, closing, and opening the doors of jail-cells, and has for its object to provide simple, positive, and inexpensive means for enabling one or more doors of a series of cells to be closed and locked or unlocked and opened from the outside of the cell and corridors thereto independently of the other doors in the series.

The invention consists in features of novelty, as hereinafter described and claimed, reference being had to the accompanying drawings, forming part of this specification, whereon—

Figure 1 is a side sectional elevation of my improved mechanism, taken on line 11 in Fig. 3, as applied to a cell-door in its closed and locked position; Fig. 2, a similar view to Fig. 1, showing the door unlocked by the mechanism; Fig. 3, a vertical transverse section, to enlarged scale, through the mechanism on line 33 in Fig. 1; and Fig. 4 a top plan of the same; Fig. 5, an end elevation of the operating mechanism seen to the left in Fig. 1, and Fig. 6 a top plan view of the sprocket wheels and chain forming part of the same.

Like letters and numerals of reference denote like parts in all the figures.

a represents one of a series of jail-cells, closed by the usual door *b*. Along the top of the door *b* is fixed the lower flanged end of a hanger-plate *c*, which projects upward through a slot 1, formed longitudinally through the floor of, preferably, a box *d*, arranged along the top of the cell *a* and extending over the entire series thereof.

To the plate *c*, at each end thereof, are pivoted two opposite rollers 2, (one on each side,) which are peripherally supported on flanged tracks or guideways 3, fixed along the floor of the box *d* adjacent to each side of the slot 1, whereby the plate *c*, with the door *b*, is adapted to travel along the box *d*.

The plate *c* is formed at the top with a rearwardly-extended horizontal portion 4, Figs. 3 and 4, having an outer vertically-dependent flanged portion 5, which is opposite and parallel to the plate *c*, the portions 4 and 5 overhanging a shaft *e*, which is arranged horizon-

tally within and along the box *d* over the entire series of cells *a* and is preferably supported and guided and adapted to be moved longitudinally between rollers *f*, which are 60 axially mounted in bearings 6, formed in brackets 7, fixed to the overhanging portions 4 and 5 of the plate *c*, or the rollers *f* may be otherwise mounted for supporting and guiding the shaft *e*, as found most suitable, or in 65 lieu of rollers the shaft *e* may be supported and guided in bearings fixed to the plate *c* or wall of the box *d*.

Vertically through the horizontal portion 4 of the plate *c*, preferably midway between its 70 ends, and immediately over the shaft *e* is formed a circular hole 8, (see particularly Fig. 3,) through which is adapted to slide a bolt *g*, having a friction-roller 9 pivoted thereto at its upper end and bearing normally 75 on its periphery against the under side of a horizontal stationary bar *h*, which is preferably channel-shaped in cross-section, arranged longitudinally within the box *d* over each cell *a*, and fixed at each end to a bracket 10, projecting from the wall of the box *d*. Vertically through the bar *h*, adjacent to each end thereof, is formed an opening 11, which is adapted to allow free passage therethrough of the roller 9 and upper end of the bolt *g*, 85 the end edges of the openings 11 being beveled outwardly from the top side of the bar *h* and the distance between the openings 11 equal to that between the closed and open positions of the door *b*.

The lower end of the bolt *g* beneath the horizontal portion 4 of the plate *c* is rounded and adapted to enter a circular hole 12, formed in the shaft *e*, and through the bolt *g*, adjacent to its rounded end, is formed a slot 13, 95 Fig. 3, which is engaged by the inner arm 14 of a lever *i* of the first order, fulcrumed to a bracket 15, which is fixed to the outside of the flanged portion 5 of the plate *c*, the other arm 16 of the lever *i* having a counterbalance-weight 17.

Bearing on and slidable along the upper side of the channel-bar *h* between its upright flanges *h*' is a flat bar *j*, in the under bearing side of which, near each end, is formed a concave recess, 18 (18'), which corresponds in contour to the periphery of the friction-roller 9 of the bolt *g*, the corners or junctions of the recesses 18 18' with the straight portion of the bar *j* being rounded, whereby when the roller 9, with the upper end portion of the bolt *g*, is projected through one of the open-

ings 11 in the bar *h* and into the corresponding recess 18, as seen in Figs. 1 and 3, on moving the bar *j* longitudinally along the bar *h* in the direction indicated by the arrow in Fig. 1 the rounded corner of the recess 18 will bear on the periphery of the roller 9 and constrain and depress the bolt *g* into engagement with the hole 12 in the shaft *e* against the resistance of the lever *i* and counterbalance-weight 17 until the apex of the roller 9 is alined to the bar *h* or in the position seen in Fig. 2, as hereinafter more particularly referred to, the distance between the two recesses 18 18' being equal to that between the openings 11 in the bar *h* and the open and closed position of the door *b*.

Across the bar *j* and pivoted to the upright flanges *h'* of the bar *h* are friction-rollers 19, which bear peripherally on the top of the bar *j* for holding it in place against the upward pressure of the bolt *g* when its roller 9 is engaged in either of the recesses 18 18'.

The bar *j* is coupled at one end to a lever *k* of the second order, which is fulcrumed to a shaft 20, mounted in bearings 20', fixed on the floor of the box *d*.

On the shaft 20, preferably at right angles to the lever *k*, is fixed an arm *l*, which is coupled at its outer free end to the upright lock-bar *m* of the door *b*, the lock-bar *m* passing freely through the floor of the box *d* into a vertically-arranged casing *n*, fixed to the front wall of the cell *a* and having an opening or keeper 21 near its lower end, through which the projecting end portion of the cross-bar 22 of the door *b* is adapted to pass, the said end portion having a notch 23 in its upper edge, which is engaged by the lower end of the lock-bar *m* in the closed position of the door *b*, which is thereby locked, as seen in Fig. 1.

The bar *j* is engaged at its other end by the free end of an arm *o*, which is fulcrumed on a shaft 24, mounted in bearings 25, fixed on the floor of the box *d*, the arm *o* having a counterbalance-weight 26.

To the free end of the lever *k* is attached one end of a wire, cord, or chain *p*, which extends to one end of the series of cells *a* and is provided thereat with a knob or handle 27 within reach of the operator and normally held, preferably by a slot 28, formed in the upper edge of a vertically-arranged plate *q*, fixed to the end of a horizontal shank 29, which is supported and slidable longitudinally in bearings 30, fixed to the wall of the box *d*, the shank 29 having a slotway 31 therethrough engaged by the arm 32 of a lever *r* of the first order, which is fulcrumed to a bracket 33, fixed to the outside of the end wall 34 of the cell *a*, the other arm 35 of the lever *r* depending from the fulcrum 33 and formed with a handle within reach of the operator.

For moving the shaft *e* longitudinally in either direction for a distance equal to that between the open and closed position of the door

b I preferably use two horizontally-arranged sprocket-wheels *s s'*, coupled to each other by the sprocket-chain *t* and having their upright spindles 36 and 37, respectively, mounted in bearings 38, fixed to the floor of the box *d*, the spindle 36 of the sprocket-wheel *s* extending downward at a suitable distance from the end wall 34 of the cell *a* and having a lower bearing 39 formed in a bracket *v*, which projects from the wall 34.

On the lower end of the spindle 36 is fixed a bevel-wheel *w*, which is engaged by a bevel wheel or pinion *w'*, fixed on a horizontal shaft 40, mounted in bearings 41, formed in the bracket *v*, and having at one end a handle *x*. The shaft *e* is fixed at its end in proximity to the sprocket-wheel *s* to one of the links of the chain *t*, whereby on partly rotating the sprocket-wheel *s* in opposite directions the shaft *e* is reciprocated longitudinally to a distance corresponding to the required movements of the door *b*, the distance between the centers of the sprocket-wheels *s s'* being arranged accordingly, with that side of the chain *t* which is fastened to the shaft *e* parallel to said shaft *e* at all times.

The end of the box *d* with the adjacent sprocket-wheel *s* and other combined operating parts of the mechanism are preferably inclosed in an end box *d'*, (indicated by broken lines in Fig. 1,) whereby tampering with or damage to the mechanism is prevented, the whole being under lock and key, controlled by the warden or operator in charge.

In operation, assuming the door *b* to be closed and locked by the lock-bar *m*, as seen in Fig. 1, in which position of the parts the bolt *g* is out of engagement with the shaft *e* and its roller 9 projecting through the opening 11 of the bar *h*, engaged in the recess 18 of the bar *j*, when it is desired to unlock and open the door *b* the operating-lever *r* is first thrown over by its handle 35 so as to move the wire-holding plate *q* by its shank 29 into the position indicated by broken lines in Fig. 1, when the plate *q*, pulling on the wire *p*, throws the lever *k* into the position indicated by broken lines in Fig. 1 and by full lines in Fig. 2. This causes the bar *j* to be moved along the bar *h* in the direction of the arrow, and in so doing the rounded shoulder of the recess 18, engaged by the roller 9, bears on the periphery of the latter and forces it, with the bolt *g*, downward through the opening 11 against the resistance of the lever *i* and counterbalance-weight 17 (seen in Figs. 3 and 4) until the apex of the roller 9 is alined to the bar *h*, the lower end of the bolt *g* meanwhile entering the hole 12 in the shaft *e*, which is thereby held to the door *b*. At the same time the arm *l* on the shaft 20 of the lever *k* raises the lock-bar *m* from the bar 22 of the door *b*, which is thereby unlocked. By then partly rotating the sprocket-wheels *s s'* and chain *t* by the handle *x* and intermediate

gearing in the direction of the arrow, as seen in Fig. 6, the shaft *e* is moved longitudinally in the corresponding direction and bearing laterally against the bolt *g* forces the roller *9* to ride under the beveled end of the opening *11* in the stationary bar *h* and along the under side of the latter and at the same time moves the hanger-plate *c* and its appendages, with the door *b*, into the open position of the latter, as indicated by broken lines in Fig. 2. In the meantime on releasing the operating-lever *r* the plate *q* with the wire *p*, lever *k*, and bar *j* are returned to their original position, as in Fig. 1, by the arm *o* and its counterbalance-weight *26*, so that when the bolt *g* reaches the open position of the door *b* it will be disengaged from the shaft *e* and its roller *9* forced through the other opening *11* in the bar *h* thereat into engagement with the corresponding recess *18'* in the bar *j* by the lever *i* and counterbalance-weight *17*.

For closing and locking the door *b* the lever *k* is again thrown over into the position shown by full lines in Fig. 2, thereby causing the bar *j*, as before described, to force the bolt *g* into engagement with the shaft *e*, which is thereby held to the door *b*, when by partly rotating the sprocket-wheels *s s'* in the opposite direction to the arrow seen in Fig. 6 the door *b* is returned to its closed position, and the lever *k* being now released and returned to the dotted position seen in Fig. 2 by the arm *o* and its counterbalance-weight *26* the lock-bar *m* is thrown into engagement with the cross-bar *22* of the door *b*, which is thereby locked.

Each door *b* of the entire series of cells *a* is equipped with its own bolt *g* for connecting and disconnecting the door *b* to and from the shaft *e*, combined with its own locking devices operated by the wire or cord *p*, as above described, independent of that part of the mechanism which moves the shaft *e* longitudinally for opening and closing all the doors of the series, whereby either of the doors *b* can be operated while the others remain normal or stationary—that is to say, assuming all the doors to be closed and locked by the bar *m*, with their operating-wires *p* out of engagement with the plate *q* and held at their outer ends or handles *27* in slots (or otherwise) formed in a fixed part of the cell-box *d* adjacent to the plate *q*, as indicated by broken lines in Fig. 1, and it being desired to operate, say, the door *b* (shown in Figs. 1 and 2) independent of the others the operating-wire *p* thereof is hitched to or engaged with the plate *q*, while the wires *p*, respectively, of the other doors remain disengaged from the plate *q*, whereby these doors are unaffected by the movement of the plate *q* and remain closed.

What I claim as my invention, and desire to secure by Letters Patent, is—

1. In mechanism of the character described, the combination with a jail-cell door, of a

hanger-plate fixed thereto and adapted to travel therewith along the front of the cell, a shaft located above and longitudinally with the door beneath an overhanging portion of the said plate and having a circumferential hole, bearings for the shaft, a bolt adapted to slide vertically through the said portion into and out of engagement with the said hole, a lever fulcrumed to the said portion and engaging the said bolt, the said lever having a counterbalance-weight, a stationary bar located above and longitudinally with the shaft beneath the said portion and having two openings vertically therethrough at points corresponding to the closed and open positions respectively of the door, a slideable bar bearing on the stationary bar and having two concave recesses in its bearing-face corresponding to the said openings and adapted therewith to be engaged by the said bolt, means for moving the slideable bar along the stationary bar and for moving the shaft longitudinally, substantially as described.

2. In mechanism of the character described, the combination with a jail-cell door, of a hanger-plate fixed thereto and adapted to travel therewith along the front of the cell, a shaft located above and longitudinally with the door beneath an overhanging portion of the said plate and having a circumferential hole, bearings for the shaft, a bolt adapted to slide vertically through the said portion into and out of engagement with the said hole, a lever fulcrumed to the said portion and engaging the said bolt, the said lever having a counterbalance-weight, a stationary bar located above and longitudinally with the shaft beneath the said portion and having two openings vertically therethrough at points corresponding to the open and closed positions respectively of the door, a slideable bar bearing on the stationary bar and having two concave recesses in its bearing-face corresponding to the said openings and adapted therewith to be engaged by the said bolt, a lever of the second order coupled to one end of the slideable bar and fulcrumed to a shaft mounted in suitable bearings, an arm on the said shaft, a lock-bar depending from the said arm and adapted to engage in a projection on the door, an arm engaging with the other end of the slideable bar and fulcrumed to a spindle having suitable bearings, the said arm having a counterbalance-weight, a wire extending from the free end of the said lever of the second order, and means for holding and operating the said wire from a suitable part of the jail, substantially as described.

3. In mechanism of the character described, the combination with a jail-cell door, of a hanger-plate fixed thereto and adapted to travel therewith along the front of the cell, a shaft located above and longitudinally with the door beneath an overhanging portion of the said plate and having a circumferential

hole, bearings for the shaft, a bolt adapted to slide vertically through the said portion and to be engaged with and disengaged from the said hole, two sprocket-wheels axially mounted in bearings, a chain engaged by the said wheels, the said shaft being fixed at one end to the said chain, and means for partly rotating the said wheels, substantially as described.

4. In mechanism of the character described,
10 the combination with a jail-cell door, of a hanger-plate fixed thereto and adapted to travel therewith along the front of the cell, a shaft located above and longitudinally with the door beneath an overhanging portion of

the said plate and having a circumferential 15 hole, bearings for the shaft, a bolt adapted to slide vertically through the said portion and to be engaged with and disengaged from the said hole, and means for moving the shaft longitudinally, substantially as described. 20

In testimony whereof I have signed my name to this specification in the presence of two subscribing witnesses.

WILLIAM DOWLING.
